UNITED STATES PATENT OFFICE.

GEORGE W. NASH, OF CHELSEA, ASSIGNOR OF ONE-HALF TO E. N. HUNT, OF READING, MASSACHUSETTS.

TOY CANNON.

SPECIFICATION forming part of Letters Patent No. 410,433, dated September 3, 1889.
Application filed January 22, 1889. Serial No. 297,118. (No model.)

To all whom it may concern:

Be it known that I, GEORGE W. NASH, of Chelsea, in the county of Suffolk and State of Massachusetts, have invented certain new and useful Improvements in Toy Cannon, of which the following is a specification.

This invention has for its object to provide an improved toy cannon adapted to hold fire-crackers while the same are being exploded; and it consists in the construction which I will now proceed to describe and claim.

Of the accompanying drawings, &c., Figure 1 represents a longitudinal section of my improved toy cannon. Fig. 2 represents a rear view of the same, the breech-block being swung aside.

The same letters of reference designate the same parts or features in all the accompanying drawings.

20 In the drawings, *a* represents the barrel, on the rear end of which is a downwardly-projecting lug or flange *b*, formed at right angles with the barrel, the rear surface of said flange and the rear end of the barrel being flush with each other.

25 *c* represents the breech-block and trail formed in a single piece, which has a flat face formed to bear closely against the rear end of the barrel and the rear surface of the flange *b*, said surface being ground smooth and even so that when held closely together they make a tight joint. The breech-block and trail is pivotally connected to the flange *b* by a screw *d*, having a head *d'*, which bears against the front side of the flange. Said screw is arranged at such a distance below the barrel that the breech-block, when turned to the position shown in Fig. 2, will uncover the barrel and permit the insertion of a fire-cracker in the rear end thereof. A groove *g* is formed in the end of the barrel to accommodate the fuse of the fire-cracker, said fuse

passing through the groove and projecting outside the barrel.

A stop-pin *h* is attached to the rear end of the barrel, in position to arrest the movement of the breech-block when the latter has been turned back into position to cover the end of the barrel. It will be seen that the screw *d* holds the breech-block and trail so that it cannot be forced back from the end of the barrel and can only be displaced by a lateral movement; hence the breech-block cannot be moved by the explosion of the cracker. The screw also enables the breech-block to be adjusted to compensate for wear of the reciprocal bearing-surfaces of the breech-block and barrel.

The barrel is provided with longitudinal flanges *i*, through which passes an axle *j*, having wheels *k*.

I claim—

In an improved toy cannon, the combination, with the barrel provided with a vent and having at its rear end a downwardly-projecting flange which is flush with the rear end of the barrel, of a breech-block and trail formed in a single piece, said piece having a close bearing on said flange and on the rear end of the barrel, and the screw or pivot connecting the breech-block and trail to the flange at a point below the barrel, said pivot being parallel with the barrel, whereby the breech-block and trail is permitted to move in a lateral direction or at right angles to the barrel, substantially as shown and described.

In testimony whereof I have signed my name to this specification, in the presence of two subscribing witnesses, this 11th day of January, A. D. 1889.

GEORGE W. NASH.
